UNITED STATES PATENT OFFICE

ALFONSO PIETRONIGRO, OF OZONE PARK, NEW YORK

SASH WINDOW

Application filed June 8, 1929. Serial No. 369,382.

This invention relates to sash windows and more particularly refers to improvements in windows of the type where the window sashes may be made to swing inwardly about a lateral hinged support, in order to facilitate cleaning and washing operations.

The primary object of this invention is to provide a window structure where window sashes of ordinary design are mounted so as to be slidable up and down while at the same time being adapted to be swung inwardly without materially disturbing the arrangement of the window frame.

Another object is to provide a sash window of the character specified in which the use of double sash frames is avoided; sash frames of ordinary design and dimensions being carried by hinged supports which are in themselves vertically slidable between the guiding strips of the window frame.

A further object is to provide a sash window combining into one the advantages of sliding and swinging sashes, the construction of which is substantially identical with that of windows and window frames in current use, except for some modifications of a simple nature which can be introduced at slight additional cost.

A still further object is to provide in a window structure of the character specified, an improved arrangement of guiding strips insuring at all times the rigidity and strength of the runways provided for the sides of the window sashes.

Other objects and advantages of the present invention will more fully appear as the description proceeds and will be set forth and claimed in the appended claims.

An embodiment of my invention is illustrated in the accompanying drawings, in which:

Fig. 1 is a front view in elevation of a window structure embodying the improvements forming the subject of my invention;

Fig. 2 is a plan sectional view in an enlarged scale taken through line 2—2 of Fig. 1;

Fig. 3 is a fragmentary vertical section taken in an enlarged scale through line 3—3 of Fig. 1;

Fig. 4 is a fragmentary front view partly

sectioned, illustrating the manner of mounting a removable part of one of the outer guiding strips;

Fig. 5 is a similar view illustrating the manner of mounting the removable part of the corresponding inner guiding strip;

Fig. 6 illustrates a constructional detail of the inner guiding strip;

Fig. 7 is a side view of the upper end of the removable part of the guide strip shown in Fig. 5;

Fig. 8 is a plan sectional view of the window showing both sashes swung within the room;

Fig. 9 is a detail vertical section through one of the sides of a sash illustrating the manner of attaching the sash weight cord to the sash so as to permit swinging movement of the sash;

Fig. 10 is a detail plan sectional view illustrating the construction of the type of hinges used in connection with the upper sash frame; and

Fig. 11 is a detail vertical section through line 11—11 of Fig. 10.

Referring to said drawings, the window frame, of ordinary construction, comprises a top 10, a sill 11 and two sides 12, 13. In said frame are mounted so as to be vertically slidable an upper sash 14 and a lower sash 15 which are off-set one from the other as shown in Fig. 3 in order to permit their independent up and down movements.

The two frames are preferably spaced in a transversal sense as shown at 16 in order to accommodate ledge 17 forwardly extending from the lower side of the upper sash frame.

The upper sash 14 slides in two runways 18, 19, formed by two rear guiding strips 20, 21 and by intermediate guiding strips 22, 23. In a similar manner the front sash slides in two runways 24, 25 formed by intermediate guiding strips 22, 23 and by front guiding strips 26, 27.

The sash frames are counterbalanced by weights 28—29, 30—31, attached to cords such as 32—33, running over pulleys 34—35 at opposite sides of the window frame.

The guiding strips 20, 22, 26 at one side of the window frame are recessed to form

longitudinal grooves such as shown at 37 in Fig. 2, forming supplementary runways through which may be slidably inserted the edges of hinge members upon which are pivotally mounted other hinge members attached to the corresponding side of the sash. Thus the left side 38 of the upper sash is mounted on hinge members 39, 40 of two hinges, the other hinge members 41 of which 5 have their front and rear edges projecting within grooves 37 formed by guiding strips 20, 22. The two hinges are vertically spaced a sufficient distance to provide a relatively long guiding support for the sash. 10 The front part of hinges 39, 40 is preferably flat, the hinge members being connected by a pivot 42 in close proximity of the surface of guide strip 22, said pivotal connection projecting no more than ledge 17 from the 15 surface of the sash frame so that clearance 16 will be sufficient to permit the sash to move unhampered up or down.

The lower sash is similarly mounted on hinge members 43, 44 pivotally connected 20 at 45 to hinge members 46 having their front and rear edges slidably inserted within longitudinal grooves 37' formed by guiding strips 22 and 26.

The hinge members carried by the lower 25 sash are preferably bent forwardly at right angle as shown at 47 so that the hinge connections 45 remain spaced a certain distance from the front surface of the sash frame.

This arrangement permits of swinging the 30 lower sash frame a relatively wide angle as shown in Fig. 8, so as to leave ample room for the swinging movement of the upper sash frame.

In Figs. 10, 11, I illustrate in detail the 35 preferred construction of hinge. In the same it is seen that the hinge member 39 is pivotally connected at 42 to the plate member which comprises a relatively wide plate 41 and another narrower plate 41' connected 40 to plate 41 by means of rivets 48 or in any other suitable manner.

Plate 41 is wider than the vertical runway 18, its front and rear edges 49, 50 extending within recesses 37 which form a supplemental 50 relatively shallow runway wider than the main runway 18.

By virtue of this arrangement, the plate member 41—41' can slide up and down the runway but cannot come off, so that it forms 55 a sliding support for the sash frame attached thereto.

In order to further insure smooth operation of the sash frames, I prefer to form the same with a recess 51 adapted to receive plate 50 41—41' when the sash frame occupies its normal position. In this manner the sash frame registers with the runway along its entire length, and a smoother operation results.

At the side of the window frame opposite

the hinged supports, the two sashes are caused to slide within runways 19, 25 respectively. In order to swing the lower sash frame 15 inwardly in the manner illustrated in Fig. 8, it is necessary to remove a section of guiding strip 27. To this end, said guiding strip is cut off for a certain length to form a gap 52 the length of which is at least equivalent to the height of each sash frame. 70

A removable strip section 53 can be placed in position to complete the guiding strip filling said gap, said strip section being preferably provided with a pin 54 downwardly projecting from its lower end, insertable through an opening 55 provided at the top 75 80 of the lower tract of strip 27.

Said removable section is also preferably provided with outwardly projecting buttons 55 adapted to be inserted and retained within frictional housings such as 56 located within the window frame, so that the movable strip section may be easily placed in position or removed therefrom. 85

In a similar manner a portion of guiding strip 23 is cut off in correspondence of gap 52 of strip 27 so as to form a gap 52' which 90 can be filled by another detachable strip section 57 as shown in Fig. 5.

Like in the previous case, strip section 57 is preferably provided at its lower end with a downwardly projecting pin 54' and at its upper end it may be provided with a handle or catch 58 pivotally mounted at 59 and adapted to be inserted within a recess 60 provided at the lower end of the upper strip section 23''. 95 100

The cut-off portion of the guiding strips is preferably near the lower end of the window frame but spaced therefrom. As a result, the stationary lower strip sections 27', 23' provide a rigid abutment for the lower sash frame when the window is closed, making it impossible for the sash to come loose of its own accord due to wind pressure or other causes. 110

The removable section 57 of guiding strip 23 is normally retained in position by the ledge portion 17 of the upper sash frame, as clearly shown in Fig. 2.

The sashes are operated in the usual manner for the purpose of ventilation. When it is necessary to clean the glass panes the strip section 53 is first removed, then the lower sash frame is raised to register with gap 52 left by the removal of said strip section. The lower sash frame can then be swung inwardly in the manner illustrated in Fig. 8, making it easy to clean or wash the outer surface of the glass pane and doing away with the necessity of a person having to set on the ledge and lean outside. 115 120 125

The upper sash is then lowered to a position where its ledge 17 clears strip section 57, and catch 58 is taken hold of at 58' so as to remove the strip section as shown in Fig. 130

5. The sash is then raised a little so as to register with gaps 52' and 52 which are substantially at the same height, and is then free to swing inwardly to the position shown in Fig. 8.

5 After cleaning the upper sash is swung back into position and strip section 57 is replaced, after which the lower sash is swung back into position and strip section 53 is replaced so as to fill gap 52.

10 It will be observed that my invention entails but few changes in the construction of window frames now currently in use; the only changes being practically the recessing 15 of the guide members at one side of the frame to provide the supplemental runways for the plate members of the hinges, and the cutting off of a portion of the guiding strips at the opposite side in order to provide a clearance 20 through which the sash frames may be caused to pass during their swinging movement.

25 Owing to the simplicity of the arrangement it is therefore possible to employ the same in connection with window frames of standard design and it is also possible to make the necessary changes in existing windows.

30 The cords from which the counterweights are suspended are preferably attached to the sash frames, by means of hooks such as 61 (see Fig. 9), this arrangement permitting the free swinging of the sash frames at their attaching side and permitting the cords being quickly detached from and re-attached 35 to the sash frames at the opposite side.

40 The constructional details of my invention may vary to a certain extent from those shown without departing from the inventive idea; the drawings will therefore be understood as being intended for illustrative purposes only and not in a limiting sense.

45 Accordingly, I reserve the right to carry my invention into practice in all those ways and manners which may enter, fairly, into the scope of the appended claims.

I claim:

50 1. In a sash window, a window frame provided with vertical runways, and upper and lower sash frames slidable within said runways, hinged structures at one side of said frame, each comprising a plate member and a hinged member pivotally connected thereto, said hinged member being attached to the corresponding sash frame, and said plate member being vertically slidable within the corresponding runway, guide members defining the runways at the opposite side of said frame, each having a removable section permitting swinging of said sash frames past 55 said guide members, when removed, said removable sections being spaced from both ends of said runways, and a sashweight detachably connected to each sash frame at said opposite side.

65 2. In a sash window, a window frame pro-

vided with vertical runways, and upper and lower sash frames slidable within said runways, hinged structures at one side of said frame, each comprising a plate member and a hinged member pivotally connected thereto, 70 said hinged member being attached to the corresponding sash frame, and said plate member being vertically slidable within the corresponding runway, guide members defining the runways at the opposite side of said frame, each having a removable section permitting swinging of said sash frames past 75 said guide members, when removed, said removable sections being close to but spaced from the lower ends of said runways, and a sashweight detachably connected to each sash frame at said opposite side.

80 3. In a sash window the combination, with a window frame provided with guide members forming vertical runways at each side thereof, and upper and lower sash frames slidable within said runways, of hinged structures at one side of said frame, each comprising a plate member and a hinged member pivotally connected thereto, 85 said hinged member being attached to the corresponding sash frame, and said plate member being vertically slidable within the corresponding runway, a section removable from each of the guide members at the opposite 90 side of said frame, permitting swinging of said sash frames past said guide members, when removed, said removable sections being substantially of the same length, and being spaced the same distance from the lower end 95 of said window frame, and a sashweight detachably connected to each sash frame at said opposite side.

100 4. A sash window structure comprising a window frame, guide members forming vertical runways at each side thereof, an upper and a lower sash frame slidable within said runways, supplemental relatively shallow runways at the base of and wider than the vertical runways at one side of said window frame, hinge structures each having a plate member projecting within and slidable within one of said supplemental runways, and a hinged member pivotally connected thereto, attached to the corresponding sash frame, 105 a section removable from each of the guide members at the opposite side of said frame, permitting swinging of said sash frames past said guide members, when removed, said removable sections being substantially of the 110 same length, and spaced the same distance from the lower end of said window frame and a sashweight detachably connected to each sash frame at said opposite side.

115 ALFONSO PIETRONIGRO.
